CLAIM

The ornamental design for a bottle lid, as shown and described.

DESCRIPTION

FIG. 1 is a top, front perspective view of a bottle lid shown in a first configuration with a drinking nozzle in a closed position.

FIG. 2 is a bottom, perspective view of FIG. 1.

FIG. 3 is a front elevation view of FIG. 1.

FIG. 4 is a rear elevation of view of FIG. 1.

FIG. 5 is a left side elevation view of FIG. 1.

FIG. 6 is right side elevation view of FIG. 1.

FIG. 7 is a top view of FIG. 1.

FIG. 8 is a bottom view of FIG. 1.

FIG. 9 is a top, front perspective view of the bottle lid of FIG. 1, shown in a condition of use.

FIG. 10 top, front perspective view of a bottle lid shown in a second configuration with a drinking nozzle in an open position.

FIG. 11 is a bottom, perspective view of FIG. 10.

FIG. 12 is a front elevation view of FIG. 10.

FIG. 13 is a rear elevation of view of FIG. 10.

FIG. 14 is a left side elevation view of FIG. 10.

FIG. 15 is right side elevation view of FIG. 10.

FIG. 16 is a top view of FIG. 10.

FIG. 17 is a bottom view of FIG. 10; and,

FIG. 18 is a top, front perspective view of the bottle lid of FIG. 10, shown in a condition of use.

The broken lines shown on the bottle lid depict portions of the bottle lid that form no part of the claimed design.
